VACUUM CLEANER FOR PARKING LOTS OR THE LIKE

Roy Charles Rush, 6129 NE. Skidmore St.,
Portland, Oreg.

Filed Jan. 16, 1962, Ser. No. 68,332

Term of patent 14 years

(Cl. D9—2)

Fig. 1

Fig. 2

Fig. 3

Fig. 4

Fig. 5

FIG. 1 is a side elevational view of a vacuum cleaner for parking lots or the like showing my new design;

FIG. 2 is a top plan view thereof;

FIG. 3 is a front elevational view thereof;

FIG. 4 is a rear elevational view thereof; and

FIG. 5 is another side elevational view thereof from the side opposite that shown in FIG. 1.

The dominant features of my design reside in the portions thereof shown in full lines.

I claim:

The ornamental design for a vacuum cleaner for parking lots or the like, as shown and described.
